UNITED STATES PATENT OFFICE.

HUGO PRAHL, OF DUSSELDORF, GERMANY, ASSIGNEE TO ERLEINISCHE METALL-WAAREN- UND MASCHINENFABRIK, OF DUSSELDORF-DERENDORF, GERMANY, A CORPORATION OF GERMANY.

PERCUSSION-FUSE WITH AN ADJUSTABLE RETARDATION DEVICE.

1,144,243.

Specification of Letters Patent. Patented June 22, 1915.

Application filed February 17, 1915. Serial No. 3,863.

To all whom it may concern:

Be it known that I, HUGO PRAHL, engineer, a subject of the German Emperor, residing at 79 Uerdingerstrasse, Dusseldorf, 5 Germany, have invented certain new and useful Improvements in Percussion-Fuses with an Adjustable Retardation Device; and I do hereby declare the following to be a full, clear, and exact description of the invention, such as will enable others skilled in the art to which it appertains to make and use the same.

My invention relates to a percussion fuse with an adjustable retardation device in 15 which the primer bolt is released by the rotation of an arm connected therewith.

My invention consists in that on the impact of the shell a lock piece protrudes and by tensioning a spring prevents the releasing arm from being rotated until the spring 20 has retracted the lock piece. By adjusting the spring it is easily possible to vary at will the retardation of the ignition on impact.

25 In the accompanying drawings I have shown two embodiments of my invention.

Figure 1 is a longitudinal section and Fig. 2 a cross section of a combined time and percussion fuse in which the percussion device 30 is provided with an arrangement according to my invention. Fig. 3 is a plan view and Fig. 4 a cross section of a slide provided for bringing the retardation device out of operation. Fig. 5 is a longitudinal section 35 and Fig. 6 a cross section of a percussion fuse constructed according to my invention. Figs. 7-10 represent detail views of this construction.

40 In the fuse shown by Figs. 1-4 there is only one primer bolt *g* pressed by a spring *p* with an inclined surface *d* against a correspondingly inclined projection *c* of the fuse frame. In consequence of this arrangement the primer bolt *g* is adapted when unlocked 45 to turn under the influence of the inclined faces pressed together, and by such rotation the recess *z* of the bolt (Fig. 2) is brought under the projection *c* whereupon the primer bolt *g* with its primer is thrown against the 50 needle *e*.

In its normal position the primer bolt *g* is prevented from being turned by the following arrangement. On the primer bolt *g* a rock arm *i* is fastened and provided with a

small double armed lever *l* pivotally mounted 55 on the rock arm *i*, one arm of the said double armed lever *l* abutting against a flattened portion of a bolt *j* and the other arm abutting against a bolt *o*. The bolt *j* is connected in any well known manner with a 60 time fusing device of any known construction in such a manner, that the flattened portion of the bolt *j* is turned away from the lever *l* some time after firing, the said time being adjusted in any ordinary way by the 65 timing device. As soon as the flattened portion of the bolt *j* releases the small lever *l* the rock arm *i* is free to be turned by the spring *p* and the inclined surfaces of *d* and *c* so that the primer bolt *g* is thrown against 70 the needle *e* in the aforesaid manner. If the shell is to be exploded by impact the bolt *o* protrudes in the moment of impact whereby the abutting arm of the lever *l* is freed so that the rock lever *i* is again rotated 75 under the influence of the spring *p* and the inclined surfaces. The primer is then thrown by the spring *p* against the needle.

According to my invention the ignition on impact can be retarded by means of the following arrangement. Behind the arm *i* and within the fuse body *d* a bolt *u* is arranged which is held back in its position of rest by a spring *q*. On impact this bolt *u* protrudes 80 beyond the edge of the arm *i* in such a manner that the said arm *i* in spite of being released by the bolt *o* cannot yet rotate because it is temporarily locked by the bolt *u* as shown by Fig. 2. As soon however as the retardation of the shell produced by the 85 impact ceases the pin *q* which was tensioned by the protruding of the bolt *o* rejects that bolt and frees the arm *i* of the primer bolt so that now ignition takes place.

In order to bring out of operation the described retardation device a slide *j* provided with a recess *w* (Figs. 2 and 3) is movable across the bolt *u* within the frame of the fuse. It is evident that the bolt *u* can protrude and retard the ignition only if the 90 recess *w* of the slide *j* is before the bolt *u*, as shown by Fig. 1. If however the slide *j* is moved in such a position that one of its non recessed parts is before the bolt then the bolt *u* cannot protrude on impact and therefore the ignition takes place without any retardation. Ordinarily the slide *j* is pressed 95 by a spring *f* (Fig. 2) against the inner sur-

face of the timing cap a provided with a recess h . If the cap is so adjusted that the recess h takes the position r shown by dotted lines in Fig. 2 the spring f presses the slides h outwardly and brings a non recessed part of the slide into the way of the bolt u . Instead of the recess h the inner surface of the cap a may be provided with a protection k^1 which if turned into the way of the slide h moves this slide inwardly thus also preventing the bolt u from protruding on impact.

The outer end of the slide h and the recess h and eventually the projection k^1 are provided with inclined edges so that they can pass each other, if the timing cap a is to be adjusted into another position.

The percussion fuse shown by Figs. 5-10 is provided with a device securing the fuse during transport and within the gun barrel the said device consisting of a body y of powder which is ignited under the impulse of firing by the primer f^1 . This body of powder burns away after the shell has moved through a certain distance after firing and if the body y is burnt completely the bursting charge can be moved forward under the influence of its spring in a well known manner. The primer bolt g^1 is under the influence of a spring p^1 pressing it with an inclined surface d^1 against a fixed inclined projection c^1 arranged on a fixed pin as shown by Fig. 5. The primer bolt is provided with a recessed disk i^1 similar in action to the released arm i of the construction shown by Figs. 1-4. If this disk like arm i^1 is free to rock the primer bolt is released and the ignition takes place.

In the position of rest the arm i^1 is prevented from rocking by a bolt o^1 held in its position before firing and some time after by the powder body y and free to protrude if the powder y has been burnt completely. If now the shell strikes against a target the bolt o^1 protrudes and thereby releases the disk like arm i^1 which then can rock so that its recess s^1 is under the projection c^1 . Therefore the primer bolt g^1 and the primer b^1 connected therewith are thrown forward against the needle e^1 . For retarding the ignition a bolt u^1 is provided which on impact protrudes into the hole x of the arm i^1 and prevents this arm i^1 from rocking in spite of its being freed by the bolt o^1 . By protruding the bolt u^1 tensions a spring q^1 which after the impact rejects the bolt u^1 whereby the arm i^1 is finally released.

In order to bring out of operation the retardation device a slide h^1 is movable within the fuse body in such a manner that it

can be moved into a groove w^1 (Fig. 7) of the retardation bolt u^1 . By redrawing this slide h^1 the retardation bolt u^1 is made free to operate in the above described manner. The slide h^1 may be connected in any convenient manner with a ring or a cap of the fuse so as to be adjusted from the outside.

Having thus described my invention what I claim is:

1. In a percussion fuse the combination of a primer bolt, an arm connected therewith, means for locking this arm and for unlocking it after the impact of the shell, means arranged so as to protrude on impact for locking said arm and a spring tensioned by this protruding action. 70

2. In a percussion fuse the combination of a primer bolt, a disklike arm connected therewith, means for locking this arm and for unlocking it after the impact of the shell, means arranged so as to protrude on impact for locking said arm and a spring tensioned by this protruding action. 80

3. In a percussion fuse the combination of a primer bolt, an arm connected therewith, means for locking this arm and for unlocking it after the impact of the shell, means arranged so as to protrude on impact for locking said arm, a spring tensioned by this protruding action and adjustable means for preventing the protruding means from 90 operation. 85

4. In a percussion fuse the combination of a primer bolt, an arm connected therewith, means for locking this arm and for unlocking it after the impact of the shell, means arranged so as to protrude on impact for locking said arm, a spring tensioned by this protruding action and adjustable slide for preventing the protruding means from 95 operation. 100

5. In a percussion fuse the combination of a primer bolt, an arm connected therewith, means for locking this arm and for unlocking it after the impact of the shell, means arranged so as to protrude on impact for locking said arm, a spring tensioned by this protruding action and a slide adjustable by means of a timing cap for preventing the protruding means from 105 operation. 110

In testimony whereof, I have signed this specification in the presence of two subscribing witnesses.
